(57) **CLAIM**

The ornamental design for a nursing bottle, as shown and described.

DESCRIPTION

FIG. 1 is a front elevation perspective view of a bottle in accordance with the invention, the rear and side elevations are the same;

FIG. 2 is a top view of the nursing bottle of FIG. 1;

FIG. 3 is a bottom view of the nursing bottle of FIG. 1;

FIG. 4 is a cross-sectional view of the nursing bottle of FIG. 1; and,

FIG. 5 is an exploded fragmentary side view of the nursing bottle of FIG. 1.

The surfaces of portions of the article not shown in the drawing or described in the specification form no part of the claimed design.
